UNITED STATES PATENT OFFICE.

MILTON E. DAVIS, OF CANASTOTA, NEW YORK.

MOP-WRINGER.

1,157,152.

Specification of Letters Patent. Patented Oct. 19, 1915.

Application filed January 30, 1911. Serial No. 605,441.

To all whom it may concern:

Be it known that I, MILTON E. DAVIS, a citizen of the United States, residing at Canastota, in the county of Madison and State of New York, have invented certain new and useful Improvements in Mop-Wringers, of which the following is a specification, reference being had therein to the accompanying drawing.

10 My invention relates to improvements in mop-wringers, and I declare that the following is a full, clear, concise and exact description thereof, sufficient to enable one skilled in the art to make and use the same, 15 reference being had to the accompanying drawings in which like reference characters refer to like parts throughout.

The object of the invention is to provide an efficient, inexpensive, device for wringing a mop, whereby the using of the hands 20 for so doing may be obviated.

The device is shown in certain modifications, besides the preferred form, all being adaptable to mops of different thickness.

25 In the drawings Figure 1 is a perspective view of the wringer detached from the pail; Fig. 2 is a plan view of the wringer seen in Fig. 1; Fig. 3 is a detail view, enlarged, of a link employed to connect the presser-board 30 with the means for moving said board; Fig. 4 is a detail view in perspective of the front board of the wringer, said view is adapted to show certain hooded openings in said part; Fig. 5 is a detail enlarged of 35 a link and its bearing employed on the device; Fig. 6 is a perspective view of a modified form of the device; Fig. 7 is a fragmentary view, showing modified means for actuating the presser-board; Fig. 8 is an elevation 40 in section showing parts of the mechanism shown in Fig. 6; Fig. 9 is a like view to Fig. 8, showing parts in different position than in Fig. 8; Fig. 10 is a side elevation in section, showing a modified manner 45 of mounting the presser-board; and Fig. 11 is a fragmentary view, somewhat enlarged, showing a modified means actuating the presser-board.

Referring more particularly to the drawings, the preferred form of structure will 50 be first described as it is illustrated in Figs. 1, 2, 3, 4 and 5. The wringer embodies sides 70 and 71 having slots 72 and held rigidly in assembled position by front board 73 provided with wings 74, 74, adapted to have 55 their lower edges rest upon the upper edge

or periphery of any ordinary pail as 80 employed for the purpose of cleaning or scrubbing. Sides 70 and 71 are provided with rear projections 75 and 76 having shoulders 60 at 77 whereby the wringer may be held at a certain elevation on the top of the pail, or the wringer may rest with the top of the pail in the end of the slots indicated at 77a. Front-board 73 has openings 78 hooded by 65 flanges 79 with braces 108. The presser-board is represented at 81 and is pivotally mounted in the lower portions of the wringer by bolts or studs 82 bearing in either recess 83 or 84 according to the bulk 70 of the mop used. The aforesaid adjustment may be made by slightly elevating presser-board 81 whereby bolts 82, 82, may be lifted 75 out of recesses 83, 83, and be readily disposed in recesses 84, 84, adapted for the use of a smaller mop. The means for forcing presser-board 81 forward or for rotating 80 it on studs 82, 82, embodies an angular shaped link 85 having journals 86 mounted in bracket bearings 87, 87, secured to the 85 plate 88 attached to presser-board 81. The remote end of the link 85 is provided with a bearing 89 having an angular approach 90 whereby spring 91 may be readily mounted or detached by slightly tipping same to 95 one side when assembling said spring 91. Spring 91 is wound upon spindle 92 and has its free extended end disposed under brackets 93, 93, and over axle 94 in the manner clearly shown in Fig. 2. Spindle 92 is 90 rigidly held to bearing arms 95, 95, secured in a suitable manner to axle or shaft 94 which is journaled in bearings in sides 70 and 71 of the wringer, and is operated by handle 96 whereby the presser-board 81 is 95 moved forwardly or rearwardly, as desired.

To use the wringer the operator places the water-soaked mop in position between board 73 and presser-board 81 which has holes 97. Obviously base A secured to the lower edge 100 of presser-board 81 and adapted to be projected forwardly under front board 73 will hold the mop in correct position. Legs B, B, hold bolts or studs 82, 82, forming journals, which bolts have been previously adjusted in bearings 83, 83, or 84, 84, in accordance with the size of the mop used. When handle 96 is moved forward, axle 94 is swung and causes its connected parts, that is; arms 95, 95, and spring 91, to move forwardly in their respective planes of rotation and hence force link 85 forwardly which in

turn forces presser-board 81 to a proper position whereby to squeeze the mop. The water oozes out forwardly through slots or recesses 78 hooded by flanges 79, and rearwardly through holes 97. The spring 91 is made of a piece of metal which is capable of bending between its bearings so that if the operator presses the handle further than the presser-board is able to move the resiliency of the spring will permit the excess of movement, that is, compensate for the undue swing of the handle. Said clearance 98 in axle 94 having been previously so disposed with relation to the turning of said axle 94, as to lie in the path of the end of link 85 when said end is forced rearwardly by the pressure of the mop upon the presser-board 81. Wings 74, 74, are adapted to direct the strain, if any, upon the upper edge of the pail employed.

The remaining figures show modifications of the device. The front piece is represented by 1, and 2 and 3 represents the side pieces which are secured thereto. A stay-bolt is illustrated by 5 showing double nuts on one end and a head on the other end for securing the sides 2 and 3 at their free edges. The side pieces 2 and 3 have depending portions indicated at 7 and 8, respectively, each being provided with a lug 9 and 10 to engage the edge of the pail, as seen in Fig. 6. Portions 7 and 8 each have preferably a tip, shown at 12, which bears against the inner face of the pail aiding in supporting the wringer 35 on the pail.

The presser-board of the wringer is represented by 15 and may be bored with holes 16 for the escape of the water, the same as may be done with the face-board 1 by holes 40 17. The presser-board 15 is to travel to and fro between the side pieces 2 and 3. At each end it has downward arm, integral or otherwise, as shown in various ways to hold the presser-board. This may be held in different 45 or in yielding positions, as indicated.

In the form shown in Fig. 8, the portion 7 has two cutouts, as at 21, the bottom of the arm 20 being provided with a headed stud at the point 22 to set into one or the other 50 of these cutouts 21, according to the size of the mop which is to be pressed, so as to take either a large or a small mop. A shaft 30 is mounted at each end in the side boards 2 and 3 and provided with a handle 32. Shaft 55 30 has secured on it the arms 33. At the end of arms 33 are links 34 pivotally mounted thereon, and at the end of each link is pivotally connected arm 35 which is connected at its other or remote end to the presser-board 15, being secured as to a cleat 36 by pin 37. A pin 38 may be placed on the cleat 36 to limit the upward swing of the arm, 35.

At 40, Fig. 7, is a curved arm pivotally mounted at the outer end of the link 34 and 65 extending through a block 41, Fig. 6, on the

arm 33, a spring 43 being carried by the curved arm and bearing at one end against the free end of the link 34 and at the other end against the block 41, or the arm by which it is carried.

As seen by reference to Fig. 9, when the lever or handle 32 is swung to the left, the parts assume somewhat such position as shown, and there is a direct movement of the presser-board against the mop as the shaft is turned and the arm 33 pushed backward. In the earlier part of the movement, as shown in Fig. 7, the spring 43 tends to keep the link 34 swung outward from the arm 33 so that pressure is applied in the front portion of the movement by reason of the position and strength of spring 43, and this pressure continues until it assumes about the position shown in Fig. 9, or in other words, until the link 34 lies directly in the line of pressure between its connection with the curved arm 35 and the presser-board. When the handle is released the tendency of spring 43 will swing the link upward. The parts may be restored to their normal position by spring 47. Fig. 7, one end of which is secured to the movable parts, as the arm 33, and the other end, as to the side 2, the swinging of the handle to compress the mop putting pressure on said spring 47 which returns the parts to their normal position when the handle is free. A modified construction of said spring 43 is shown in Fig. 11 where the spring 45^a has each end connected with the swinging members, so that the action of the handle in pressing the mop compresses the spring as well. The equivalent of this return spring is shown also at 47^a in Fig. 6.

Various modified constructions may be employed by the ordinary mechanic which would still be within the spirit and scope of this invention.

In Fig. 1, I have shown adjustable members 105, 105, slidingly secured to wings 74, 74, by headed screws 105^a, 105^a. Said members 105, 105, are for the purpose of allowing for the difference in slant to some pails that may be employed.

As seen in Fig. 3, arms 9 may be provided with bores, indicated at 107, to receive spindle 92 and thereby adapt the device for different sized mops.

Having thus described my invention, what I claim as new and desire to secure by Letters Patent is:

1. In a mop wringer, a front-board, side members and a presser board, said side members having depending portions provided with a plurality of cutouts and the presser board having studs whereon to swing the presser board from any pair of such cutouts.
2. In a mop-wringer, a front-board, side members having depending portions with a plurality of cutouts, said cutouts being

adaptable for the interchangeable mounting of a presser-board, a presser-board, means for actuating said presser-board upon its mounting and for permitting it to yield at 5 any point in squeezing a mop.

3. In a mop-wringer of the character described, a front-board, side members and a presser-board, said front-board having wings adapted to engage with the top edge 10 of a pail and means slidingly mounted upon said wings whereby to adjust the height of the mop-wringer with reference to the edge of the pail, substantially as described.

4. A mop-wringer having a front-board 15 with ends extended beyond the edge of the pail and members slidingly mounted on the said ends whereby to adjust the height of the wringer above the pail, side pieces cut-out to provide a recess for the top of the 20 pail, the parts which depend within the pail having lugs bearing against the pail supporting said parts clear of the pail.

5. In a mop-wringer, the combination of 25 side pieces provided with depending portions, each having a plurality of recesses at the lower end, a presser-board with depending portions adapted to mount the board interchangeably in a selected pair of said recesses, a shaft, an arm carried thereon, a lever member pivoted on the presser-board, a link connecting the arm and the lever member and a spring operative by the rotation of the shaft to cause pressure of the 30 presser-board whereby by reason of a given mounting of the presser-board and the action of the spring to adapt the wringer to act on mops of different size.

6. In a mop-wringer, the combination of a 40 movable presser-board, a bent lever hingedly mounted thereon, a shaft having arms projecting therefrom with a spindle supported

thereon and a spring supported on the spindle, one end bearing on the shaft and the other engaging the end of the bent lever whereby the spring acts both as a lever to 45 move the presser-board and as a resilient member to take up excessive pressure.

7. In a mop-wringer having a movable 50 presser-board, a link hinged thereon, a spring-lever bearing at one end on the link, its other end having a permanent support and the lever being supported between its ends on a swinging member by the movement of which member the strength of the 55 spring is applied to the movement of the presser-board.

8. In a mop-wringer, the combination of 60 a movable presser-board, a lever hinged thereon, a rotating shaft with projecting means for the support of a spindle, said means being adapted for the support of the spindle at various points, and a spring carried by the spindle with one end bearing on the rotating shaft and the other engaging 65 the end of the lever.

9. In a mop-wringer, the combination of 70 a movable presser-board, a link hinged thereon, a rotating shaft, arms on the shaft, a spindle in the arms and a spring carried by the spindle operative by the rotation of the shaft to move the presser-board, the arms being adapted to hold the spindle in different positions whereby to adapt the movement of the presser-board to different 75 sizes of mop.

In testimony whereof I hereunto affix my signature in the presence of two witnesses.

MILTON E. DAVIS.
